UNITED STATES PATENT OFFICE.

NICHOLAS F. ACKERMAN, OF DULUTH, MINNESOTA.

MEANS FOR REPAIRING FURNACES.

1,270,749.

Specification of Letters Patent. Patented June 25, 1918.

Application filed September 6, 1917. Serial No. 190,076.

To all whom it may concern:

Be it known that I, NICHOLAS F. ACKERMAN, a citizen of the United States, and resident of Duluth, in the county of St. Louis and State of Minnesota, have invented certain new and useful Improvements in Means for Repairing Furnaces, of which the following is a specification.

This invention relates to means for repairing furnaces.

One of the objects is to repair a furnace without cooling or laying out the same.

Another object is to provide novel means which is inserted into a furnace whereby the latter may be quickly repaired.

Another object is to provide a device by means of which furnace roofs may be repaired in a manner to meet the various requirements for successful commercial use.

These and other objects are accomplished by providing a device of the class described including means which is insertible into a furnace and which forms a support for a portion of the furnace being repaired.

The invention is illustrated on the accompanying sheet of drawings in which Figure 1 is a side elevation, parts being in section, of a furnace, a charging machine, and my repair mechanism associated therewith; and

Fig. 2 is a fragmentary sectional view of the same taken in the plane of line 2—2 of Fig. 1.

The various novel features of my invention will be apparent from the following description and drawings and will be particularly pointed out in the appended claims.

Referring particularly to the figures of the drawings it will be noted that I have shown, generally speaking, an open hearth furnace 10, a charging machine 11, and means 12 whereby the roof of the open hearth furnace may be repaired. It is well appreciated that in the operation of furnaces of the type mentioned, it is frequently necessary to repair the same for the reason that the parts thereof become seriously deteriorated as a result of being subjected to heat of extreme temperatures. It is a very expensive matter to cool down a furnace, or to lay it out. For this reason it is highly essential to repair furnaces while they are in operative condition. To this end I have provided my novel device whereby portions of the furnace may be repaired in a manner

to meet the various commercial requirements.

This repair means 12 includes a longitudinally extending hollow member 13 having a vertical hollow portion 14 which terminates in an enlarged hollow head 15, the upper surface 16 of which, in this particular instance, is made to conform with the shape of the inner surface of the roof 17 of the furnace 10. In view of the fact that the roof of a furnace of this type is usually the part which needs repair most frequently, I have shown the form or supporting head 15 shaped and arranged in a manner to facilitate the repairing of furnace roofs. However, it will be appreciated that other parts of the furnace may be repaired by any other suitable support having the required shape. It will be noted that this supporting head 15 is inserted into the furnace through a doorway 18 thereof, and in this instance is connected to the peel 19 of the charging device 11 of any standard and well known type. After the supporting head 15 is inserted into the furnace the same may be moved longitudinally, vertically or rotated, so that the supporting surface 16 may be placed in its proper position to conform with the surface of the roof by the usual charging machine mechanism which is capable of giving the peel such movements. It is seen, therefore, that the supporting head 15 may be properly placed for supporting the brick of the part of the roof to be repaired. Of course it is to be understood that this repairing device need not necessarily be supported by the peel 19 or any other part of a charging machine, for it is readily apparent that the same may be supported and operated manually or by other suitable mechanism which is not associated with charging machines. However, in view of the fact that most furnaces of this type are provided with charging machines I choose to illustrate my invention in connection therewith.

In view of the fact that the furnaces of this nature are subjected to extremely high temperatures it is essential that my repair device be protected against such excessive temperatures. To this end I have provided means for maintaining parts of this device relatively cool, or at least sufficiently cool to accomplish the desired results. It will be noted that I have provided a water inlet 110

2

pipe 20 through which water may pass from any suitable source to a water distributing center 21 from which the water is distributed in various directions to different parts of the hollow head 15 whereby the head is maintained in a cool condition to be of effective use in repairing the furnace roof. The pipe 20 preferably extends longitudinally through the hollow member 13, its vertical portion 14, and into the hollow head 15 from which the cooling water passes downwardly through the vertical portion 14 and then through the member 13 and out through a pipe 22. By supplying cooling water continuously to the parts in question while said parts are being used for repairing a portion of the furnace, work may be effectively accomplished without cooling down the furnace or laying the same out. After the furnace has been repaired the repair supporting parts may be withdrawn from the furnace through the door opening 18 thereof. In case it is supported upon the peel 19 of a charging machine, the same may be detached from the peel.

It is evident that there may be various modifications of the invention herein particularly shown and described, and it is my intention to cover all such modifications which do not involve a departure from the spirit and scope of my invention as set forth in the following claims.

I claim:

1. In mechanism of the class described, means which is movable with respect to a furnace and which includes a fluid cooled hollow head for supporting a portion of the furnace being repaired.
2. In mechanism of the class described, means which is movable with respect to a furnace and which includes a hollow head for supporting a portion of the furnace being repaired, and means for supplying a cooling medium to said hollow head for cooling purposes.
3. In mechanism of the class described,

means which is movable with respect to a furnace and which forms a support for a portion of the furnace being repaired, and cooling means for said first mentioned means.

4. In mechanism of the class described, means movable with respect to a furnace including a hollow supporting head, and a water supply operatively connected to said hollow head for cooling purposes.

5. In mechanism of the class described, means which is movable with respect to a furnace and which includes a hollow supporting head, and a pipe in said hollow head from which water may be supplied to the head for cooling purposes.

6. In mechanism of the class described, means which is movable with respect to a furnace and which includes a longitudinally extending hollow member having a vertical hollow portion terminating in a hollow head, and a pipe extending through said longitudinally extending member and vertical portion and into said head for conveying a cooling medium thereto.

7. In mechanism of the class described, means which is movable with respect to a furnace and which includes a longitudinally extending hollow member having a vertical hollow portion terminating in a hollow head, a pipe extending through said longitudinally extending member and vertical portion and into said head for conveying a cooling medium thereto, and means whereby the water from said head may be discharged.

8. In mechanism of the class described, means which is movable with respect to a furnace and which includes a head the upper surface of which is rounded to support the roof portion of a furnace as it is being repaired, and means for cooling said first mentioned means.

Signed at Duluth, Minnesota, this 29th day of August, 1917.

NICHOLAS F. ACKERMAN.
